UNITED STATES PATENT OFFICE.

CHARLES GUSTAV MELLSTROM, OF LONDON, ENGLAND.

BREECH MECHANISM FOR ORDNANCE.

SPECIFICATION forming part of Letters Patent No. 545,902, dated September 10, 1895.
Application filed December 12, 1893, Serial No. 493,458. (No model.)

To all whom it may concern:

Be it known that I, CHARLES GUSTAV MELLSTROM, civil engineer, a subject of the King of Sweden and Norway, residing at Victoria Mansions, 32 Victoria Street, London, England, have invented certain new and useful Improvements in and Relating to Quick-Firing and other Breech-Loading Ordnance, of which the following is a specification, reference being had to the accompanying drawings.

This invention relates chiefly to quick-firing guns, but parts of it are applicable to other breech-loading guns for increasing the strength and durability of the breech and for facilitating the action of the breech mechanism.

The main object of the said invention is to construct a quick-firing gun, of that class wherein a screw breech-block is employed, in such a manner that the breech requires no lateral aperture for the insertion and withdrawal of the breech-block, which is carried on a vertical hinge or pivot at the side of the breech, and can be inserted into and withdrawn from the gun by a simple movement about its hinge or pivot.

The said invention consists partly in adapting the breech for the reception of a novel form of breech-block and in the peculiar construction of the said block and method of actuating the same. The said breech-block has projecting screw-threaded portions fitted to engage with similarly screw-threaded segmental portions in the gun, so that by turning the said block about its axis in the gun the screw-threaded portions of the block will engage with or be disengaged from those in the gun in the usual manner. The said block is supported in a carrier and thereby hinged or pivoted at the side of the breech end of the gun. I attach the block to the carrier by its head or outer end in such a manner that the block is supported and held firmly by the carrier as it is moved into and out of the gun. Heretofore segmental screw breech-blocks have been usually made cylindrical or parallel sided along their screw-threaded portions. They have also, though not commonly, been made conical, so that the small end of the block projects inward and closes the breech; but according to the present inven-

tion I employ a breech-block, which is reversely tapered or coned—i. e., it is tapered along its screw-threaded portions in such a manner that its largest diameter is at its inner end. It is constructed and operated as hereinafter described.

The accompanying drawings show the breech of a gun provided with the present improvements.

Figure 1 is an elevation of one side of the breech. Fig. 2 is an elevation of the other side of the said breech. Fig. 3 is a rear elevation of the same. Fig. 4 is a horizontal longitudinal central section through the breech and breech-block, showing the breech closed. Fig. 4^a is a rear view of the safety mechanism, the operating-lever being removed. Fig. 5 is a section on the line x x, Fig. 3, showing the breech open. The remaining figures show details of the mechanism, drawn to a larger scale.

Like letters and figures indicate corresponding parts throughout the drawings.

A is the breech portion of the gun. A' is the screw-threaded chamber therein. B is the breech-block. C is the carrier. D is the lever for operating the breech-block. C' is the hinge or pivot of the carrier. E is the extractor. As above stated, the breech-block B is inserted and withdrawn by moving it about the hinge at C'—that is to say, it does not have to slide endwise through the carrier. Nevertheless I do not have to curtail its length. It may be of the ordinary length of a screw breech-block, but as the breech has no lateral opening throughout its entire circumference the chamber A' and the block B must be so formed that the block can move freely through the chamber in the arc of a circle about the axis of the hinge C' in opening and closing the breech, and yet when home and locked in the chamber it must securely and tightly close the breech. For this purpose the said chamber has its sides shaped in longitudinal section, as shown in Figs. 4 and 5—that is to say, the two sides of the chamber are arcs of circles whose center is the axis of the pivot C' and which have such radii as will allow sufficient clearance for the sides of the block B to pass without touching them in entering and leaving the said chamber.

I prefer that the hinge or pivot C' of the

carrier C be arranged about midway between the outer and inner ends of the screw-threaded chamber, as shown. It will be observed that the carrier and the part B* of the block that engages therewith are screw-threaded and have the screw-threads continuous all around the same.

It is obvious that a reversely coned or taper breech-block which is moved to lock and unlock the same by the action of its peripheral screw-thread on a screw-thread in the breech of the gun, must not have a screw-thread consisting of a spiral with a continuously and uniformly increasing diameter from the small to the large end of the cone, for, if so formed, such convolution or turn of the screw-thread in moving forward to close the breech would pass from a part of the spiral groove in the gun in which it has a firm bearing to another part of the said gun of larger diameter and would therefore cease to be efficiently supported in the breech at the time when the most efficient support is required. I therefore form the spiral or screw thread as follows—that is to say, commencing with the smaller end of the cone and taking a line from one to the other end along the exterior of the same, I form the first turn of the screw-thread so that it has the same diameter and a uniform pitch or longitudinal advance entirely around the block. Then continue the spiral from the termination of this turn or convolution of the thread on the said line so as to form the next turn or convolution with a larger diameter, but in the same manner, (i.e., without increase of diameter)—that is to say, the spiral or screw-thread of the cone consists of a series of turns or convolutions, each of which is concentric with the axis of the cone entirely around the same and merges into a convolution of larger diameter toward the forward end of the cone with a uniform or continuous inclination or pitch from one to the other end of the same. I complete the said cone by planing off or otherwise removing portions of the screw-threads, and then the said reversely-coned breech-block has two or more portions of its periphery consisting of a series of spiral segments of a uniform pitch suitable for insuring the necessary endwise movement of the block, but each complete turn having all of its segments of equal radius. Therefore, in turning the breech-block to cause its screw-threads to engage with those in the gun, the threads in the different segments of the block will turn and advance in the grooves in the gun so as to force the block into close contact with the breech while maintaining a firm bearing and support therein.

Instead of making each single complete turn of the screw-thread of a different diameter from the preceding turn, I may make the block in steps—that is to say, with two or more complete turns of the thread of one diameter and next to them two or more turns of a larger diameter, and so on throughout the length of the cone. It will be obvious that the screw-

threads in the gun must correspond with those of the block. I may use screw-threads which are V-shaped, as shown, or which are square or otherwise suitably shaped in cross-section.

For turning the breech-block about its axis to lock and unlock it and for moving it with the carrier about its hinge I provide the outer end of the block with a circular toothed segment or series of teeth at B', preferably arranged below its axis, and 1 gear with this toothed segment a segmental pinion F on a vertical shaft F', which is supported in suitable bearings C² on the hinged carrier C, and which has attached to or formed with it the operating-lever D of the breech mechanism. The said pinion has only as many teeth as are necessary to keep in gear with the segment B' on the block B to turn the latter a sufficient distance about its axis to move the screw-threads thereon into and out of gear with those of the gun. In the turning of the block about its own longitudinal axis it moves endwise through a short distance by reason of the pitch of the screw-threads, and therefore the teeth on the said block approach the axis about which the pinion F turns. To prevent inconvenience from this movement I make the teeth of the pinion eccentric to the shaft F', as shown in Fig. 13, which is a plan of the lever and pinion detached, and in which 1 is the center of the shaft and 2 the center of the segment. Therefore as the block B moves backward the teeth of the pinion recede therefrom, and vice versa when the block moves forward the teeth of the pinion approach the same. If I make the segments of the block and chamber with parallel fillets instead of with screw-threads, this eccentricity of the toothed pinion will not be necessary. The said lever, moreover, has a shoulder at D', arranged to act as a stop to the rotation of the pinion when the same has been turned through about a quarter of a revolution by means of the operating-lever D, as shown in Fig. 5. This stop then comes in contact with the back surface of the carrier C, and can move no farther relatively to the carrier. Therefore from this position the continued movement of the lever D tends to turn the carrier C about its axis C' in the proper direction to withdraw the breech-block from the gun and move the same clear away from the breech-aperture. Thus it will be seen that in a gun provided with my improvements the breech-block in opening the breech has only two movements—viz., rotation on its own axis and a circular movement about the vertical hinge or pivot, which movements are effected by one continuous movement of the operating-lever in one direction, the closing of the breech being effected by similar movements of the reverse order and direction.

The breech-block B carries a firing-pin G, which is shown detached in side and end elevation in Figs. 15 and 16. This pin extends through a central hole in the block. I prefer

to use a firing-pin which is semiannular or trough-shaped in transverse section, except at its rear and forward ends. In the trough or curved portion of the said pin I place a spiral spring G' , which bears against the forward end of the pin at G^2 and is so arranged that it will be compressed when the latter is drawn back to cock the gun.

In the ordinary working of the gun the 10 cocking is effected by the rotation of the block B about its axis in unlocking or releasing the block from the gun. For this purpose I provide the said block with a helical or cam surface B^2 , (most clearly shown in Fig. 6,) 15 which is a section of the block B detached. Said surface engages with a lug or projection G^3 , Figs. 15 and 16, on the rear end of the firing-pin G. The said firing-pin is so controlled that it is kept from rotating with the block. 20 during the cocking action, and the helical surface of the block is so arranged that as the block rotates its action on the lug G^3 of the firing-pin forces the same backward into engagement with the trigger mechanism. For 25 guiding and preventing the rotation of the firing-pin in the block I insert into the head of the latter a piece II, formed to cover the aperture through which the said pin is inserted into the block. This piece II is passed 30 over and held in place by the pivot pin or bolt F' of the operating-lever, and when the said bolt is removed can be taken out of the block to afford access to the firing-pin or permit the insertion or removal of the same. 35 Said piece II forms the rear bearing for the spring G' .

The firing-pin has at its rear end a hook G^0 projecting through the carrier and through a slot II' in the said piece II, and the firing-pin is thereby prevented from turning about its axis while being cocked. By means of the said hook the firing-pin can be cocked in case of a missfire without moving the breech-block.

40 The extractor E is a lever pivoted near the carrier-hinge at E' , and has an arm or pair of arms E^2 of the ordinary kind extending into the proper position to engage with the rim of a cartridge in the gun, as shown. The tail 45 end E^3 of the extractor is arranged to be struck by a shoulder C^3 on the carrier, as the latter is turned upon its hinge C' to open the breech.

The trigger mechanism comprises various 50 parts, which are shown detached in Figs. 17, 55 18, 19, and 20. A retaining catch or sear I is formed or fixed on an arm I' , the stem I^0 , of which is pivoted to the carrier at I^5 , Fig. 10, in the proper position to engage with a projection or shoulder G^4 of the firing-pin G, when the same has been drawn back by the action of the helical or cam-surface B^2 of the breech-block. The outer end of the said pivoted arm I' is bent or cranked, as shown at I^2 , so 60 that it projects into a position wherein it will be actuated by an arm K, fixed on the end of a pin or bolt K' , which projects through

the side of the breech-chamber, and the outer end of which is provided with a trigger K^2 . A spring I^3 is arranged in combination with 70 the pivoted arm I' to act thereon to press the catch or sear I into engagement with the firing-pin.

In combination with the trigger mechanism I may sometimes employ a safety device, 75 consisting of a small spring-controlled lever R, Fig. 21, pivoted at R' and provided at one end with a projection R^2 , that, until the parts are ready for firing, passes through the carrier into a hole or recess I^4 in the aforesaid 80 pivoted arm I' and holds the sear so that it cannot release the firing-pin; but when the operating-lever is properly home it compresses the spring R^3 of the said lever R and raises the bolt out of the hole or recess I^4 in 85 the pivoted arm I' , so that the latter can be actuated by the trigger to release the firing-pin and fire the gun.

In breech mechanism, wherein a screw breech-block is supported with a capability 90 of rotation about its axis in a carrier which withdraws the block from the gun, the said block while moving in and out of the gun has its screw-threads totally disconnected from those of the gun. Therefore it is necessary to provide means for holding the block immovably in the carrier while it is out of the breech-chamber, so that when the block has been pushed home again in the said chamber, its screw-threads will be in exactly the 95 same position relatively to those in the chamber as they were when the said block had been turned on its axis to unlock it, but before the carrier had commenced to turn about its hinge. For this purpose I employ a spring 100 pin or catch L, Figs. 3 and 5. (Shown detached in end view and longitudinal section in Figs. 22 and 23.) This catch is so arranged in the carrier C that when the breech-block B has been turned on its axis to unlock it from the gun a recess B^4 (see Figs. 8 and 9) in the 105 said block comes opposite the said spring-catch, so that the latter engages therewith and holds the block B so that it cannot be displaced by turning about its axis while moving 110 with the carrier C about the hinge or pivot C' of the latter. I prefer to place over the aperture in which the said spring-catch is placed a cover-plate screwed into the carrier. The 115 spring-catch L has a hollow or tubular stem L' 120 from which projects a toe L^2 . Inside the hollow stem I place the spiral spring which abuts against the said cover-plate, so as to press the catch into engagement with the recess in the block. Until the block B has been turned so 125 that its screw-threads are released from those in the gun the toe L^2 lies in a groove C^3 in the carrier; but when the block is ready to move out of the breech the toe is opposite the recess B^4 in the screw-thread in the block, and by the 130 action of the spring is pushed in the said recess as soon as the carrier commences to swing round on its hinge, and the block is thereby kept from turning about its axis. In closing

the breech when the carrier comes in contact with the end of the gun the projecting catch L, Fig. 5, is forced back and thereby its toe is disengaged from the said recess in the block and pushed back into the groove in the carrier. The block is then free to turn in the carrier.

To avoid accidents from hang-fire I provide the gun with a device which will prevent the premature opening of the breech if the cartridge in the gun does not explode when the trigger is pulled. For this purpose I prefer to employ a safety appliance which consists essentially of a pendulum arranged in combination with the breech mechanism to prevent the movement thereof until the gun has completed its recoil after a discharge—that is to say, if the charge has been fired the said pendulum under the influence of the energy of the recoil in which it has participated continues to move in the direction of the recoil after the recoil action has ceased and will release the lever of the breech mechanism, so that the breech can be opened; but if the charge has not been fired the said pendulum remains inoperative—that is to say, the pendulum does not act by reason of its inertia at the beginning of the recoil, but by its momentum at the termination of the recoil.

I combine this device with my improved breech mechanism as follows—that is to say, I suspend the pendulum M by its arm on a pin or stud M', fixed in any convenient position to the gun or suitable moving part of the mounting. I provide the said pendulum with a hook-shaped arm M². A latch D² is fixed on the operating-lever D in such a position that the hook-shaped arm M² on the pendulum will engage with the said latch and remain in engagement therewith before and until the gun is fired, the said arm M² being pressed into engagement with the latch by a suitable spring M³. When the gun is fired, the said pendulum, moving with the gun in its recoil, acquires sufficient momentum to act very efficiently, as above described, to release the operating-lever, so that the breech can be opened; but if the charge hangs fire, and consequently there is no recoil, the pendulum remains inoperative and the said lever is not released. In combination with this device I arrange an elastic plate N, having a stud or projection N', which is arranged to engage with a recess M⁴ in the hooked arm of the pendulum and hold the same after recoil out of engagement with the latch D² until the lever D has been pulled back to open the breech. On the side of the elastic plate N is an incline N², arranged in combination with a similar incline d on the latch of the lever D, so that in turning the said lever about its pivot F' to open the breech the said inclines will act to push the projection N' of the plate out of engagement with the pendulum to allow the latter to resume its normal position. I prefer that this mechanism should be inclosed by a casing O at the side of the

gun, as shown in Fig. 4. This improved pendulum device may be employed with either a recoil or non-recoil mounting. The effect of a pendulum acting with the energy which it has acquired in the recoil movement of the gun, even though such movement should be very slight, as in the case of a non-recoil mounting, will always be sufficient to release the lever, and in this respect my improved device is advantageously distinguishable from those in which a pendulum is arranged to act by its inertia at the commencement of the recoil movement. It might happen in some instances when the gun is laid at a high elevation that the operating-lever, through the concussion caused by the discharge, will escape from the control of the aforesaid safety device. I therefore provide an additional retaining device, as follows—that is to say, I form a recess d⁰, Figs. 13 and 14, in the said lever and place therein a spring-latch P, formed with an arm P', which projects through the said lever and lies at the side of the handle D^X. The nose P² of the latch is arranged to enter a socket or recess P³ in the carrier and thereby hold the lever D so that it cannot move away from the same; but in grasping the handle to open the breech the hand also grasps the arm P', which is thereby pressed inward and releases the latch and the lever D will then be free to move outward, as required.

What I claim is—

1. The combination with the breech end of a gun, of a taper, screw-threaded or filleted breech-block having its smaller end at the rear, substantially as described.
2. The taper, screw-threaded or filleted breech-block having its forward end larger than its rear end and each convolution of screw thread of uniform radius but of greater diameter than the adjoining convolution nearer the outer end of the block, portions of the block being removed at the sides, in combination with a breech similarly shaped and screw-threaded substantially as described.
3. The taper, screw-threaded or filleted breech-block having its forward end larger than its rear end and each convolution of screw thread of uniform radius but of greater diameter than the adjoining convolution nearer the outer end of the block, portions of the block being removed at the sides, in combination with a breech similarly shaped and screw-threaded, but curved laterally to admit of the withdrawal of the block when unlocked, and a carrier connected with the block by a continuous screw-threaded part and hinged to the side of the breech about midway between the two ends of the block, substantially as described.
4. The taper, screw-threaded or filleted breech-block having its forward end larger than its rear end and each convolution of screw thread of uniform radius but of greater diameter than the adjoining convolution nearer the outer end of the block, portions of the block

- being removed at the sides, in combination with a breech similarly shaped and screw-threaded but curved laterally to admit of the withdrawal of the block when unlocked, and 45 a carrier connected with the block by a continuous screw-threaded part and hinged to the side of the breech about midway between the two ends of the block an operating lever formed with a slightly eccentric segment 50 wheel hinged to the carrier and faced with a toothed segment formed on the breech-block, whereby the breech can be opened or closed without moving the block endwise, through the carrier by a continuous movement of the 55 operating lever in one direction, substantially as described.
5. The taper, screw-threaded or filleted breech-block having its forward end larger than its rear end and each convolution of 60 screw thread of uniform radius but of greater diameter than the adjoining convolution nearer the outer end of the block, portions of the block being removed at the sides in combination with a breech similarly shaped and 65 screw-threaded, but curved laterally to admit of the withdrawal of the block when unlocked, and a carrier connected with the block by a continuous screw-threaded part and hinged to the side of the breech about midway between the two ends of the block, the inclined 70 surface B^2 on the block and the firing pin formed with the inclined surface G^3 for cocking the said pin when the breech-block is turned about its axis, substantially as described.
6. The taper, screw-threaded or filleted breech-block having its forward end larger than its rear end and each convolution of screw 75 thread of uniform radius but of greater diameter than the adjoining convolution nearer the outer end of the block, portions of the block being removed at the sides, in combination with a breech similarly shaped and screw-threaded but curved laterally to admit 80 of the withdrawal of the block when unlocked, and a carrier connected with the block by a continuous screw-threaded part and hinged to the side of the breech about midway between the two ends of the block, the catch or sear I, releasing trigger K, and 85 spring controlled retaining lever R which latter is turned out of engagement with the sear by the operating lever D when the breech is closed, substantially as described.
7. The combination with the breech end of 90 a gun, of the taper, screw-threaded or filleted breech-block having its smaller end at the rear, the operating lever thereof, and means whereby the lever is locked until the termination of the recoil and is then automatically 95 unlocked, substantially as described.
8. The combination with the breech end of 100 a gun, of the taper, screw-threaded or filleted breech-block having its smaller end at the rear, the operating lever thereof, a hooked finger D^2 on the operating lever, a weighted lever M^2 engaging said finger D^2 until the termination of the recoil and then acting by its momentum to liberate the finger D^2 , substantially as described.
9. The combination with the breech end of 105 a gun, of the taper, screw-threaded or filleted breech-block having its smaller end at the rear, the operating lever thereof, a hooked finger D^2 on the operating lever, a weighted lever M^2 engaging said finger D^2 until the termination of the recoil and then acting by its momentum to liberate the finger D^2 , and 110 a spring catch N to maintain said lever M^2 in its raised position when the latter has moved to liberate the finger D^2 substantially as described.
- In testimony whereof I have hereunto set my hand this 29th day of November, 1893.
